SPECIFICATION forming part of Design No. 22,763, dated August 29, 1893.

Application filed August 1, 1893. Serial No. 482,137. Term of patent 8½ years. Patented in England March 3, 1893, No. 208,527.

To all whom it may concern:

Be it known that I, FREDERIC AUMONIER, trading as Wm. WOOLLAMS & Co., a subject of the Queen of Great Britain, and a resident of 110 High Street, near Manchester Square, London, England, have invented a new and original Design for Wall-Paper, (patented in Great Britain on the 3d day of March, 1893, No. 208,527,) of which the following is a specification.

This design of wall paper as illustrated in the accompanying drawing consists of scrolls and peony and other flowers extending from such scrolls. In one square there are three peony like flowers and three sprays of smaller clematis like flowers arranged together just above the meeting parts of two scrolls, one spray of peony flowers falling over one of the

scrolls and in the other square the scrolls are arranged at a somewhat different angle to the 20 previously mentioned scroll and have just above their meeting parts a smaller bunch of peony and clematis like flowers, a spray of clematis like flowers falling over one of the scrolls.

The two figures are arranged alternately at 25 an angle.

I claim—

The design for wall paper substantially as herein shown and described.

FREDERIC AUMONIER.
